PORTABLE SHAMPOO TRAY

Gaye G. Cates, 1708 S. Monroe,
San Angelo, Tex. 76901

Filed June 11, 1971, Ser. No. 152,484

Term of patent 14 years

Int. Cl. D28—03

U.S. Cl. D86—10 F

FIG. 1

FIG. 2

FIG. 3

FIG. 4

FIG. 5

FIG. 1 is a front perspective view of a portable shampoo tray showing my new design;

FIG. 2 is a top plan view thereof;

FIG. 3 is a right side elevational view;

FIG. 4 is a front elevational view; and

FIG. 5 is a rear elevational view.

I claim:

The ornamental design for a portable shampoo tray, as shown.
